CHAIR SPRING CONSTRUCTION

John J. Bond, Milwaukee, Wis., assignor to No-Sag Spring Company, Detroit, Mich., a corporation of Delaware

Filed Feb. 14, 1966, Ser. No. 527,169

9 Claims. (Cl. 267—102)

This invention relates generally to an improved chair spring, and more particularly to an improved spring that is especially adapted for use in the seat of a chair.

Seat springs having a variety of characteristics must be available to furniture manufacturers to accommodate the different types of chairs that are available on the market for the purpose of pleasing the individual purchaser of these chairs. It had been the practice to rely chiefly upon coil springs for a seat spring assembly in which the characteristics of the spring assembly are varied by utilizing coil springs of different strengths and lengths. Spring assemblies of this type perform excellently but are expensive to manufacture and require the manufacturer to carry a large inventory of different types of individual coil springs.

In an effort to reduce the cost of seat springs, the use of sinuous springs in seat spring assemblies has become prevalent. Sinuous spring assemblies are less expensive than coil spring assemblies and they do provide satisfactory performance in some applications. However, they do not produce as comfortable a seat as coil springs do and it is not as convenient for the manufacturer to vary their characteristics to accommodate the different types of seats. Accordingly, quality chairs still use coil spring assemblies in their seats to provide the best performance.

It is therefore a general object of the present invention to provide an improved spring assembly that is especially adapted to be used in seats.

It is another object of the present invention to provide a spring assembly having characteristics which closely resemble the characteristics of a coil spring assembly but which is appreciably less expensive to produce.

Another object is to construct the spring in units, which may be employed in any desired multiple to produce the desired width of the spring assembly.

Another object is to provide a spring construction in which the characteristics of the spring may be adjusted by changing various lengths of one or more of the spring elements while utilizing the same gauge wire.

Another object is to provide an improved spring construction that may be formed by simple bending of the spring wire as opposed to coiling the wire or forming it into a sinuous configuration.

A further object is to provide an improved furniture spring of simple and inexpensive but sturdy construction, which is efficient in operation.

According to this invention the improved furniture spring construction is formed in units that are employed in multiples. The quantity of units utilized depends upon the required width of the entire spring assembly. The several units are coupled to each other by front and rear edge wires for mutual cooperation to form a spring assembly.

Each of the spring units comprises a pair of inclined front arms extending upwardly from the front of the furniture frame and toward the rear of the seat in parallel relationship. A pair of similar inclined rear arms extend upwardly and rearwardly from the rear of the furniture frame in parallel relationship. One of the front arms is coupled to its cooperating rear arm by a horizontal support bar while the other front arm is coupled to its cooperating rear arm by a second horizontal support bar. The front and rear arms are formed of spring wire to render them yieldable so that a weight on top of the spring unit will cause them to move downwardly to produce a concomitant downward movement of the horizontal sup-

2

port bars which carry the seat padding. The two front arms, the two rear arms and the two horizontal support bars may be formed by the simple bending of a single strand of spring wire. However, since the greatest load is applied to the rear arms, a reinforcing spring is connected thereto for the purpose of absorbing a portion of the load to relieve the rear arms of excess strains.

A wire tie loop, preferably of rectangular configuration, is connected to the two horizontal support bars for tying them together to prevent their lateral displacement relative to each other. The wire loop extends forwardly of the two horizontal support bars to serve as a support for the front portion of the seat padding and upholstery.

The several spring units are tied together by a front edge wire and a back edge wire. The front edge wire is clipped to the front edges of the several tie loops of the several units. In like manner, the back edge wire is clipped to the rear edges of the several tie loops of the spring units. Thus, each of the tie loops connects the two horizontal bars of each spring unit together, while the front and back edge wires connect the several spring units together to prevent their lateral displacement relative to each other and to couple them for cooperative operation.

The foregoing and other objects of the invention, which will become more fully apparent from the following detailed description, may be achieved by means of the apparatus described in connection with the accompanying drawings in which:

FIGURE 1 is a plan view of a seat spring assembly incorporating the features of the present invention;

FIGURE 2 is a side elevational view of the spring assembly illustrated in FIGURE 1; and

FIGURE 3 is fragmentary perspective view depicting a portion of the spring assembly shown in FIGURE 1.

Reference is now made more particularly to the drawings which illustrate a seat spring assembly incorporating the features of the present invention. The spring is shown mounted on a wood frame generally identified by the reference numeral 10 and comprising a pair of side plates 11 and 12 which are connected by a front crossbar 13 and a rear crossbar 14 as clearly illustrated in FIG. 1. The spring assembly comprises a plurality of spring units 15 mounted on the wood frame 10 in mutually cooperating relationship to form a spring assembly for a seat.

Each of the spring units 15 is of identical construction so that it will only be necessary to describe one of them. Moreover, identical parts in the several spring units will be identified by identical reference numerals in the drawings. Each of the spring units 15 includes a pair of front arms 19 and 20. A short leg 23 extends from the arm 19 and is joined thereto by a sharp angle so that it forms an angle with the arm 19. In like manner, a short leg 24 extends from the arm 20 so that the leg 24 and the arm 20 form an angle. The short legs 23 and 24 are connected to each other by a tie bar 21 which is rotatably supported in the bore of a tubular portion 18 of a bracket 22.

The back portion of the spring unit 15 includes a pair of rear arms 28 and 29 that extend upwardly and rearwardly of the rear crossbar 14 of the frame 10. The arm 28 terminates in a U shaped portion 30 which extends through the bore of a tubular section 31 of a bracket 32 with the crossbar of the U shaped portion 30 being rotatably supported in the tubular section 31. In like manner, the rear arm 29 terminates in a U shaped portion 35 and the crossbar of the U shaped portion being rotatably supported in the bore of a tubular section 36 of the bracket 32. Since the U shaped portions 30 and 35 are rotatably supported by the bracket 32, the rear arms 28 and 29 can pivot relative to the bracket 32. The U shaped portions 30 and 35 extend upwardly from the rear crossbar 14 and the rear arms 28 and 29 extend rearwardly at an angle to the U shaped portions 30 and 35. However,

in addition to being pivotable relative to the bracket 32, the rear arms 28 and 29 are yieldable relative to the U shaped portions 30 and 35 and move downwardly relative thereto when a load is applied to them from the top.

The front arms 19 and 20 cooperate with the rear arms 28 and 29 to provide a resilience which contributes to the comfort in the seat of the chair. To this end, the front arm 19 is connected to the rear arm 28 by a horizontal support bar 39 while an identical horizontal support bar 40 connects the front arm 20 to the rear arm 29. The front arms 19 and 20 and the rear arms 28 and 29 are yieldable relative to the support bars 39 and 40 which further contributes to the resiliency of the spring unit when a load is applied upon the horizontal support bars 39 and 40.

The front arm 19 is parallel to the front arm 20 while the horizontal support bar 39 is parallel to the horizontal support bar 40. In like manner, the rear arm 28 is parallel to the rear arm 29. It is therefore apparent that the front arm 19, the horizontal support bar 39 and the rear arm 28 form one side of the spring unit 15 and are all in a single plane that is transverse to the frame 10. Similarly, the front arm 20, the horizontal support bar 40 and the rear arm 29 comprise the second side of the spring unit 15 and are in a second plane that is parallel to the first plane.

In order to facilitate manufacture, the portion of the spring unit 15 described above is produced from a single strand of spring wire which is bent to the desired configuration in a simple bending press. Thus, the two U shaped portions 30 and 35, the two rear arms 28 and 29, the two horizontal support bars 39 and 40, the two front arms 19 and 20, the two short legs 23 and 24 and the tie bar 21 are all formed by bending a single strand of wire. The bending can be accomplished very rapidly and efficiently in a press with the assistance of suitable dies.

When the spring unit 15 is incorporated in the spring assembly for a seat, the greatest loads are applied to the rear arms 28 and 29 to place great strain on these members and their associated connecting elements. For example, a person usually drops himself onto the seat when sitting down to apply an unusually high load to the rear portion of the spring assembly. Such high load causes exceptionally large flexures between the rear arms 28 and 29 and their connected elements. For example, a great amount of flexure would occur between the rear arms 28 and 29 and their cooperating support bars 39 and 40 respectively. As a result, the greatest strains are applied to these members and their associated parts.

In order to relieve these parts from such excessive strains, a reinforcing coil spring 65 is connected to absorb a portion of the load. The spring has one end anchored in the bracket 22 and has its opposite end connected to one end of a cable 66. The opposite end of the cable is connected to a plate 67 which is fixedly secured to both of the adjacent upstanding legs of the two U shaped portions 30 and 35. This arrangement serves to connect the coil spring 65 to both rear arms 28 and 29.

The rear arms 28 and 29 are pivotable relative to the frame 10 by reason of the rotatable mounting of the U shaped portions in the bracket 32. As a result a load applied to the top of the spring assembly will cause a simultaneous pivoting movement of the arms 28 and 29 in a clockwise or downward direction as viewed in FIGURE 2. Such downward movement will cause a flexure at the juncture of the horizontal support bars 39 and 40 with the rear arms 28 and 29 respectively. The coil spring 65 avoids an excessive amount of such flexure by absorbing a part of the load through its connection with the rear arms 28 and 29. Thus, as the arms 28 and 29 pivot downwardly the U shaped portions 30 and 35 will pivot with their associated arms. Since the coil spring 65 is connected to both U shaped portions it will begin to stretch and thereby resist the downward pivotal movement of the arms 28 and 29. As the downward pivotal movement in-

creases the resistance of the spring 65 increases progressively so that it absorbs a part of the load. As a result, the flexure between the support bars 39 and 40 and their associated rear arms 28 and 29 is reduced at high loads.

If a positive stop were introduced to prevent such excessive flexing, the spring would bottom, resulting in uncomfortableness to the user. The spring 65 prevents excess flexing and yet avoids the undesirable bottoming. As the load on the spring increases, the spring becomes stiffer by reason of the action of the spring 65 but the spring still possesses the desired resiliency. At normal loads, the spring 65 offers relatively little resistance to the flexing of rear arms 28 and 29 with respect to their associated parts but when a relatively high loading occurs, and particularly an impact load, the spring 65 produces a high resistance to excess flexing.

The two sides of the spring unit 15 are prevented from being displaced laterally relative to each other to retain them in operating relationship by a wire loop generally identified by the reference numeral 45. The wire loop 45 is of elongated rectangular configuration and includes a pair of parallel side wires 46 and 47 joined at one end by an end wire 48 and at the opposite end by an end wire 49. The wire loop 45 is also formed of a single length 25 of wire with its ends being joined by a clip 50 which also embraces the horizontal support bar 39 for securing the loop 45 thereto. The side wire 46 of the loop 45 extends along the length of the horizontal support 39 and is disposed in engagement therewith. In like manner, the side wire 47 of the loop 45 lies along the length of the horizontal support bar 40 and also engages it. Additional clips 51 are applied to secure the wire loop 45 to the horizontal support bars 39 and 40.

The forward portion of the wire loop 45 extends forwardly beyond the terminus of the horizontal support bars 39 and 40 so that the front end 49 of the loop 45 is disposed approximately above the front edge of the crossbar 13. This forward portion of the loop 45 serves as a support for the front portion of the seat padding and its associated upholstery. The forward extremity of the loop 45 is bent upwardly a slight amount to provide a proper support to the front edge of the seat.

Each spring unit 15 includes one of the wire loops 45 for securing the two sides of the spring together for cooperative action. The spring assembly includes several spring units 15 to produce the desired seat width. In the exemplary embodiment, four spring units 15 are provided to complete the spring assembly for a chair seat. These four spring units are connected to each other by a front edge wire 55 and a back edge wire 56. The front edge wire 55 extends along the upper front edge of the spring assembly and engages each of the end wires 49 of the several wire loops 45. The edge wire 55 is secured to the end wire 49 of each of the loops 45 by a clip 57. The 55 extremities of the edge wire 55 are bent inwardly into engagement with the side wires of the end wire loops 45 and are secured thereto by clips 58.

The rear edge wire 56 is similarly mounted in the spring assembly. It extends along the upper rear edge of the spring assembly and engages each of the end wires 48 of the several loops 45. The rear edge wire 56 is attached to each of the end wires 48 by clips 59. The extremities of the rear edge wire 56 are bent inwardly to engage the side wires of the two end loops 45 and are secured thereto by clips 60. Thus, the front edge wire 55 and the rear edge wire 56 tie the several spring units 15 together so that they may mutually cooperate to produce a spring assembly which is particularly well adapted to be used as a spring for seats.

The spring construction of the present invention produces the superior characteristics of a coil spring but is appreciably more economical to manufacture inasmuch as the parts of the spring may be readily formed of spring wire and assembled together. Moreover, the characteristics of the spring assembly of the present invention may

be adjusted without changing the gauge of the wire by simply changing the lengths of the front arms 19 and 20 and the rear arms 28 and 29. Thus, the stiffness of the spring may be increased to the desired extent by the simple expedient of reducing the length of the rear arms 28 and 29. Of course, when a more flexible spring is desired, the length of the arms 28 and 29 are increased proportionately. In certain types of seats it is desirable that when a person sits on the seat the rear portion of the seat be depressed to a greater extent than the forward portion of the seat. This characteristic may be easily obtained with the present spring assembly by reducing the length of the front arms 19 and 20. Thus, by merely changing the length of the front arms 19 and 20, the desired differential in the depression between the front and rear portions of the spring assembly may be obtained. The front arms 19 and 20 may be increased to the extent that a flat depression of the spring assembly will be obtained wherein the front portion of the spring and the rear portion of the spring yield the same amount upon the application of a load.

From the foregoing detailed description of the construction and operation of the illustrative embodiment of the present invention it will become apparent that a new and improved chair spring construction has been provided in which the superior characteristics of a coil spring are obtained with appreciably less expensive construction, and the characteristics of the spring may be readily adjusted to suit the particular application by the simple expedient of changing the rectilinear dimensions of specific elements of the assembly without changing the gauge of the wire employed.

Although the illustrative embodiment of the present invention has been described in considerable detail for the purpose of making a full disclosure of a practical operative arrangement by means of which the invention may be practiced, it is to be understood that various novel features of the invention may be incorporated in other arrangements without departing from the spirit and scope of the invention as defined in the subjoined claims.

The principles of the invention having now been fully explained in connection with the foregoing description of embodying structure, I hereby claim as my invention:

1. In a furniture spring assembly mounted on a frame; a plurality of front spring arms; means mounting said front spring arms to said frame for pivotal movement relative to said frame; said plurality of front spring arms extending angularly from the frame and being resiliently movable toward and away from the frame; a plurality of rear spring arms; means mounting said rear spring arms to said frame for pivotal movement relative to said frame; said plurality of rear spring arms extending angularly from the frame in spaced relationship to said front spring arms and being resiliently movable toward and away from the frame; said front and rear spring arms extending generally in a rearwardly direction; and a plurality of support bars for receiving the load to be applied to the spring assembly with each of said support bars having a resilient connection with one of said front arms and with one of said rear arms for cooperative operation.

2. A spring assembly according to claim 1 including; load absorbing means connected to said rear spring arms to absorb portions of loads applied to the spring assembly for preventing excessive strains on said rear springs.

5 3. A spring assembly according to claim 2; wherein said load absorbing means comprises a spring having one end anchored to the frame and its other end connected to said rear arms to yieldably resist the resilient movement of said rear arms when a load is applied to the spring assembly with the resistance increasing as the load on the spring assembly increases.

10 15 4. A spring assembly according to claim 1 including; means connecting pairs of said support bars to prevent their lateral displacement relative to each other so that the two connected support bars and their associated front arms and rear arms comprise a spring unit, a plurality of said spring units being mounted on the frame to comprise a spring assembly.

20 5. A spring assembly according to claim 4; wherein said connecting means comprises a wire loop formed of two side wires and two end wires, and including clips attaching each of said side wires to one of said support bars.

25 6. A spring assembly according to claim 5 which includes a plurality of said spring units; including coupling means coupling said wire loops to each other consecutively to unite the several spring units into a spring assembly.

30 7. A spring assembly according to claim 6; wherein said coupling means comprises a front edge wire clipped to the front end wire of each of said wire loops; and a rear edge wire clipped to the rear end wire of each of said wire loops.

35 8. A spring assembly according to claim 4 including; a front bracket mounted on the frame; means mounting said two front arms to said front bracket for pivotal movement relative to said frame; a rear bracket mounted on the frame in spaced relationship to said front bracket; and means mounting said two rear arms to said rear bracket for pivotal movement relative to said frame.

40 45 9. A spring assembly according to claim 8 including; a tie rod coupling the two front arms of each spring unit together, said tie rod being supported by said front bracket for rotational movement to render said two front arms pivotable relative to the frame; and said mounting means for said two rear arms extends from said rear arms and is rotatably supported by said rear bracket to render said rear arms pivotable relative to the frame.
